UNITED STATES PATENT OFFICE.

SAMUEL GEISMAN, OF NEW YORK, N. Y.

DESIGN FOR AN ARTICLE OF MANUFACTURE.

48,783.

Specification for Design.

Patented Mar. 28, 1916.

Application filed January 13, 1916. Serial No. 71,986. Term of patent 7 years.

To all whom it may concern:

Be it known that I, SAMUEL GEISMAN, a citizen of the United States, residing in the city of New York, borough of Manhattan, in the county and State of New York, have invented a new, original, and ornamental Design for an Article of Manufacture, of which the following is a specification, reference being had to the accompanying drawing, forming part thereof.

The figure is a plan view of my new design to be applied to an article of manufacture.

I claim:

The ornamental design for an article of manufacture, as shown.

SAMUEL GEISMAN.

Witnesses:

JOSEPH GEISMAN,
A. L. KITCHIN.
